UNITED STATES PATENT OFFICE.

EUGÈNE DANIEL, OF PARIS, FRANCE, ASSIGNOR TO THE ROXBURY CARPET COMPANY, OF BOSTON, MASSACHUSETTS.

DESIGN FOR CARPETS.

Specification forming part of Design No. 9,351, dated June 27, 1876; application filed June 8, 1876.
[Term of Patent 3½ years.]

To all whom it may concern:

Be it known that I, EUGÈNE DANIEL, of No. 14 Rue Bleu, Paris, in the Republic of France, have invented a certain new and original Design for Carpets, of which the following is a specification:

The nature of my design is fully represented in the accompanying photographic illustration.

What I claim as my invention is—

A design for a carpet, as represented in the accompanying photographic illustration.

In testimony whereof I have signed my name to this specification in the presence of two subscribing witnesses.

EUGÈNE DANIEL.

Witnesses:
